UNITED STATES PATENT OFFICE.

HAWLEY PETTIBONE, OF NEW ROCHELLE, NEW YORK.

APPARATUS FOR PROPORTIONING AND MIXING GAS.

SPECIFICATION forming part of Letters Patent No. 696,107, dated March 25, 1902.

Application filed August 8, 1900. Serial No. 26,260. (No model.)

To all whom it may concern:

Be it known that I, HAWLEY PETTIBONE, a citizen of the United States, residing at New Rochelle, in the county of Westchester and State of New York, have invented certain new and useful Improvements in Apparatus for Proportioning and Mixing Gas; and I do hereby declare the following to be a full, clear, and exact description of the invention, such as will enable others skilled in the art to which it appertains to make and use the same.

This invention relates to a proportioning and governing valve for mixing different kinds of gas, such as water-gas and producer-gas or gas and air, for use as fuel and for power in gas-engines.

The object of my invention is to provide convenient and automatic apparatus for correctly proportioning and governing the flow of different kinds of gas and the delivery of a mixture of gases in the desired proportion and volume for the work required.

My apparatus is designed particularly for mixing large volumes of gas, such as producer-gas and water-gas, in the proper proportions for use as a fuel in all kinds of metallurgical operations and for power purposes in gas-engines, wherein a mixture of water-gas and producer-gas has been found most effective in running large engines of several hundred up to several thousand horse-power.

The devices and combinations of parts constituting my invention herein will be set forth in the claims.

I will now describe the details of construction of my improved apparatus by reference to the accompanying drawings, in which—

Figure 1 represents a vertical section, with parts in elevation, of my proportioning and governing valve apparatus. Fig. 2 represents a side elevation, partly in section, illustrating the thermostatic device and its connections with a gate in one of the cup-valves.

My proportioning and mixing valve apparatus is constructed with a suitable cylindrical shell A, which is divided by horizontal partition-plates a a' into the receiving gas-chambers B B' , respectively, at top and bottom of the shell and the central mixing gas-chamber B'. The cylinder is also provided with top and bottom plates a^2 and a^3 , and to the latter plate is secured a drip-pipe a^4 for

carrying off water of condensation. An inlet-pipe b for producer-gas connects with chamber B, and a smaller inlet-pipe b' for water-gas connects with chamber B' . An outlet-pipe b^2 for mixed gas connects with the central chamber B'. Upon the top plate a^2 is constructed a water-tank C for the governing-holder D. A guide-tube c for the valve-rod E is secured centrally to the plate a^2 and rises in tank C above the water-line. Suitable guide rods or standards c' c^2 are secured to the side of tank C and form guides and bearings for the wheels on the holder D. The top of standard c^2 is also provided with a fulcrum-support c^5 for the counterbalancing-lever M. A small equalizing gas-pipe c^3 , having a valve c^4 , connects the outlet gas-pipe b^2 with the interior of the gas-holder D, rising therein above the water-line, and such pipe is connected with plate a^2 by a fitting v , which is bolted to the plate. The central valve-rod E is secured by a suitable fitting and screw-bolts d' to the top of the holder D, and an inverted tube d is secured to the rod within the holder and works over the upright tube c , making a sealed passage for the valve-rod E.

The upper end of rod E is screw-threaded and has connected to it a coupler d^2 , having an eye or staple, to which is connected the chain d^3 , which in turn connects with the upper end of the curved bearing n at the end of the counterbalance-lever or rocking arm M. The valve-rod E passes down through the tubes c and d and thence through the gas-chamber B and into the gas-chamber B', where it connects with both of the cup-valves F and H. The cup-valve F is preferably made cylindrical with a closed bottom and with numerous ports f in its cylindrical portion, which are preferably of rectangular form and extend from the bottom plate to near the top of the cup. The bottom plate of the cup F is provided centrally with a hemispherical concave portion f' for making a ball-joint connection with the valve-rod. The valve-rod E is provided with a half-ball e , having its convex portion upward and adapted to fit in the concave f' . The rod E is screw-threaded where it passes through the half-ball e and above and below the same and has applied to it above the concave f' a washer e' and a

lock-nut e^2 . The half-ball e is provided at its under side with a nut p , which is made integral with it, and both the half-ball and nut have an internally-screw-threaded opening, 5 the nut p serving for the application of a wrench to adjust the half-ball in the proper position on rod E . The horizontal partition a is provided with a central opening large enough to receive the cup F , and to the under side of the partition is secured the annular valve-seat G , of any suitable material, to form a bearing or seat for the annular flange f^3 of the cup and make a tight joint therewith. When the valve F is closed on its seat, 10 as shown, no gas can pass from chamber B into the mixing-chamber B' . To the lower end of the valve-rod E is loosely connected a hemispherical concave socket f^2 , to which is connected the spider e^5 , which is attached 15 to the sides of the lower cup-valve H . Below the socket f^2 and within the same is secured the half-ball e^6 and its nut e^7 , which are made in one piece. A washer e^8 and lock-nut e^4 are applied to the rod E above the socket for 20 properly adjusting and holding in place the ball-joint for holding valve H in exact position to make a tight joint with its annular seat G' . The cup-valve H is provided with ports h in its cylindrical wall and has a large 25 opening h' cut in its bottom, and is also provided with an annular flange h^2 , which fits up against the annular valve-seat G' . This annular valve-seat is secured by screw-bolts g' to the partition-plate a' . In the interior 30 of the cup-valve H is fitted an extra cup I , having rectangular ports i , which are adapted to register with the valve-ports h . This cup I serves as a gate for varying the size of the ports h in cup H for varying and regulating 35 the relative proportion of water-gas admitted from chamber B^2 into the mixing-chamber B' . To the bottom of the regulating-cup I is secured a yoke or hanger i' , extending down into the chamber B^2 and having 40 at its lower end a squared angular opening, in which is fitted the upper end of the operating-rod K . This rod K is provided with an arm k , and its lower end is seated in a suitable bearing in the bracket or standard 45 L , which is secured to the bottom plate a^2 . To the arm k is pivotally connected the rod l , to the outer end of which is pivotally connected at b^3 the screw-threaded rod l' , which latter passes out through the bracket m , as 50 shown in Fig. 1.

The nut l' , having a handle, is applied to the screw-threaded end of rod l' and has a bearing in the bracket m , so that by turning it to the right or left the rods l and l' can be 55 pushed inward or outward, thereby turning the rod K and the regulating cup or gate I for more or less closing or opening the ports h in the cup-valve H .

I preferably use a thermostat-regulator, as 60 illustrated in Fig. 2, for automatically controlling and regulating the cup or gate I to

deliver a mixed gas of uniform calorific power, regardless of the proportions of the two gases.

My thermostatic regulator may be constructed as follows: I provide a small drop-tube boiler R , which is connected by a trap-pipe r with the bottom of chamber T , which is supported on legs t^2 or in other convenient manner. To the top of chamber T is secured circumferentially a flexible diaphragm t , to 70 which is applied a weight t' . A pipe c^6 , having a valve c^7 for mixed gas, connects with the outlet-pipes b^2 and extends down to a perforated burner-coil c^8 below the boiler R , where the mixed gas is burned for heating the boiler. 80 A bell-crank lever $l^4 l'$ is pivotally connected at l^5 to a bracket on the side of the gas-chamber and connects at its lower end with the rod l' , and its upper end rests on the diaphragm t or pivotally connects with the weights t' . 85 Any suitable liquid—as water, ether, or alcohol—is placed in the vaporizer or boiler R . If the mixed gas delivered by the pipe b^2 and branch pipe c^6 grows richer, a hotter flame will be produced at the burner c^8 , thereby increasing the pressure in the vaporizer R , which pressure will be immediately transmitted to the diaphragm t , raising the weight t' and lever-arm l^6 , which will act to draw out the rod $l l'$, thus partly rotating the regulating cup or gate I and partly closing the ports h in the cup H of the water-gas valve. A smaller proportion of water-gas will therefore be admitted to the mixing-chamber B' , and the mixture will consequently possess 95 less heating power or a lower calorific value. When the mixed gas delivered by pipe b^2 is too lean or too low in heating power, the pressure on the diaphragm t will be decreased, allowing the same to drop, thereby pushing 100 in the rod $l l'$ and more fully opening the ports h in the water-gas valve H , thereby admitting a larger proportion of water-gas to the mixing-chamber B' . This thermostatic device is quite sensitive and the parts act 105 quickly and automatically to control the calorific power of the gas delivered by pipes b^2 to the burners in furnaces, &c.

The walls of the gas-chambers B B' B^2 are provided with large openings having removable plates or doors x x' x^2 for giving access to the cup-valves and their connections.

The counterbalancing-lever or rocking arm M is connected by a pin m' to the fulcrum-support c^5 and is provided at its opposite ends with the curved bearing-plates $n n'$. A chain o is connected to the upper end of the bearing-plate n' and connects at its lower end with the rod p' , which supports the counter-weights P .

The apparatus having been constructed and arranged substantially as above described, the valves are properly adjusted to their seats by pulling them up into position, then slackening or loosening the lock-nuts, such as e^2 , and the washer e' . The valve F can now be accurately adjusted with its bearing-flange f^3

upon the seat G, the socket f' in the bottom of the valve turning freely upon the half-ball e, so that every part of the circumferential flange shall bear closely upon the seat G and make a tight joint therewith. This having been effected, the nut e² and washer are turned tightly against their bearings, thereby holding the valve rigidly in position on the rod E. The cup-valve H will be adjusted in a similar manner upon the rod E for making a tight joint with its seat G'. In order to decrease or lessen the proportion of water-gas admitted from chamber B² into the mixing-chamber B', the cylindrical gate I will be slightly turned for partially covering the ports h of the cup-valve, such operation being performed by means of the screw-nut l² on the rod l' outside of gas-chamber B². If it is desired to increase the proportion of water-gas admitted into chamber B', then the gate I is turned in the opposite direction to more widely open the ports h. It is to be noted that the yoke or hanger i', having a squared opening in its lower end, slides up and down on the squared rod K as the valve H rises or falls.

There may be further provided with each valve pieces of metal for blocking off or partially closing the ports in cup-valve F, so that in case a mixture richer in water-gas is desired than is obtainable by opening the lower valve H to its full extent the quantity of producer-gas admitted to mixing-chamber B' may be lessened.

In practice producer-gas made according to the Loomis process and consisting principally of carbonic oxid, a small per cent. of hydrogen or marsh-gas, and nitrogen is supplied from a separate holder through the sixteen-inch gas-inlet b to the gas-chamber B, and at the same time water-gas, also made by the Loomis process and consisting of carbonic oxid, hydrogen, and marsh-gas or other carbureted hydrogen, is supplied from a separate holder through the ten-inch inlet b' to the chamber B². The valve on the outlet-pipe b² or its connecting-pipes, leading to a furnace or gas-engine, being open and the cup-valves F and H being open, the two kinds of gas in chambers B B² will pass through their respective valves into the mixing-chamber B', where they will mix in the proper proportions and pass off through pipes b² to the place of use. When there is a full consumption of gas from the delivery-main b², the pressure falls in such pipe and in that way relieves the pressure of gas on holder D. This lowering of the pressure takes place through the medium of the small pipe c³. As the pressure of gas falls in the governing-holder D such holder falls, more widely opening the cup-valves F and H, permitting the flow of larger volumes of gas. When the consumption of gas at the burners or gas-engines decreases, the gas backs up in the pipe b², thereby increasing the pressure on the holder D, forcing the same upward, thereby partially closing the valves F and H and shutting off or reducing the vol-

umes of gas admitted through such valves to the mixing-chamber B'.

It will be evident from the above that the valves F and H move up and down as the demand for gas at the burners or gas-engines increases or decreases, the valves being automatically actuated by the governing-holder D.

The counterweights P on the rod p', connected to the outer end of the counterbalance-lever M, are used not only to counterbalance the weight of the valves F and H and the rod E, but can be readily removed or replaced, so that in case a heavier pressure is required on the delivery-gas-main part of the weights are taken off, causing the valves F and H to close or move toward their seats under heavier pressure of gas on the delivery-main. Again, if a less pressure is required it is obtained by adding more weights P, thereby counteracting part of the weight of the holder, &c., and causing the holder to move under lighter pressure.

Having described my invention, what I claim, and desire to secure by Letters Patent, is—

1. In a gas proportioning and mixing apparatus, two gas-receiving chambers and an intermediate mixing-chamber, separated one from the other, by partition-plates, each having a valve-opening and an annular seat, a cup-valve having ports and bearing on said seat, a governing-holder above said gas-chambers, a rod connecting said holder with said cup-valves, means connecting with one of the cup-valves for varying the size of its ports and a pipe connection from the mixing-chamber to the governing-holder, substantially as described. 100 105 110 115 120 125

2. In a gas proportioning and mixing apparatus, the combination with two gas-receiving chambers, two connected supply-valves having ports, and a governing-holder connecting with said valves for supplying gases of different calorific value in the desired proportions, of means for delivering a mixed gas of fixed and uniform calorific value, consisting of a mixing-chamber having a gas-delivery pipe, and connections with said supply-valves, a regulating-gate in one of said supply-valves, a thermostatic device, operating devices connecting the thermostat with said regulating-gate, and a small gas-pipe connecting with the delivery-pipe for mixed gas and terminating in a burner of the thermostatic device, whereby the delivery of mixed gas of a uniform calorific value is automatically effected, substantially as described. 110 115 120 125 130

3. In a gas proportioning and mixing apparatus, two gas-receiving chambers and an intermediate mixing-chamber, separated one from the other, by partition-plates, each having a valve-opening and an annular seat, a cup-valve having ports and arranged to bear, one on each seat, a governing-holder above said gas-chambers, a rod connecting with said holder, and having a ball-and-socket connection with each of said cup-valves, whereby

the valves may be accurately adjusted on the rod to make tight joints with their annular seats, and a pipe connection from the mixing-chamber to the governing-holder, substantially as described.

4. In a gas proportioning and mixing apparatus, the combination with two gas-chambers separated by a partition having a valve-opening and an annular seat, of a governing-holder above the same, a cup-valve having an attached socket, and adapted to bear on said seat, a valve-rod connecting with said holder and having a ball or part ball, and means for engaging the latter with said socket for accurately adjusting said valve on the rod to make a tight joint with its annular seat, substantially as described.

5. In a gas proportioning and mixing apparatus, two adjacent gas-chambers separated

by a partition-plate, having a valve-opening 20 and an annular seat, in combination with a cup-valve having ports in its wall, a cylindrical gate in said cup and having ports arranged to register with the ports thereof, a yoke connecting with said gate and having 25 an angular opening at its lower end, an operating-rod working in said opening and having a lateral arm, and a jointed rod pivotally connecting with said arm, and extending through the wall of the chamber, whereby the 30 gate may be turned in the cup-valve to control the ports thereof, substantially as described.

In testimony whereof I affix my signature in presence of two witnesses.

HAWLEY PETTIBONE.
